(57) **CLAIM**

The ornamental design for a desk with a lamp, as shown and described.

DESCRIPTION

FIG. 1 is a perspective view of a desk with a lamp; FIG. 2 is right side view of the desk with a lamp of FIG. 1, the left side view being a mirror image thereof; FIG. 3 is a front view of the desk with a lamp of FIG. 1; FIG. 4 is a rear view of the desk with a lamp of FIG. 1; FIG. 5 is a top plan view of the desk with a lamp of FIG. 1; and, FIG. 6 is bottom view of the desk with a lamp of FIG. 1. The broken lines depict portions of the desk with a lamp that form no part of the claimed design.

1 Claim, 5 Drawing Sheets
